US0D1005376S

(12) **United States Design Patent** (10) **Patent No.:** **US D1,005,376 S**
(45) **Date of Patent:** **** Nov. 21, 2023**

(54) **TRIPOD**

(71) Applicant: **SHENZHEN JIKE DIGITAL TECHNOLOGY CO., LTD.**, Shenzhen (CN)
(72) Inventor: **Zhuangxiaoyi Chen**, Shenzhen (CN)
(73) Assignee: **SHENZHEN JIKE DIGITAL TECHNOLOGY CO., LTD.**, Shenzhen (CN)

(**) Term: **15 Years**

(21) Appl. No.: **29/880,587**

(22) Filed: **Jul. 25, 2023**

(51) LOC (14) Cl. **16-05**

(52) U.S. Cl.

USPC **D16/244**

(58) **Field of Classification Search**

USPC D16/214, 219, 240, 242, 243, 244, 245,
D16/250

CPC G03B 15/03; F16M 11/24; F16M 11/28;
F16M 11/32

(57) **CLAIM**

The ornamental design for a tripod, as shown and described.

DESCRIPTION

FIG. 1 is a perspective view of a tripod showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 a perspective view of the tripod where the tripod is in a configuration of use;

FIG. 10 is a perspective view of the tripod where the tripod is in a folded state;

FIG. 11 is an exploded perspective view of the tripod;

FIG. 12 is a perspective view of a stand of the tripod, shown separately for illustration;

FIG. 13 is another perspective view thereof;

FIG. 14 is a front elevational view thereof;

FIG. 15 is a rear elevational view thereof;

FIG. 16 is a left side elevational view thereof;

FIG. 17 is a right side elevational view thereof;

FIG. 18 is a top plan view thereof; and,

FIG. 19 is a bottom plan view thereof.

The broken lines in the drawings depict portions of the tripod that form no part of the claimed design.

1 Claim, 19 Drawing Sheets
